UNITED STATES PATENT OFFICE.

OSCAR BROCKMAN, OF LOUISVILLE, KENTUCKY.

DESIGN FOR A VENDING VEHICLE.

60,395.

Specification for Design.

Patented Feb. 14, 1922.

Application filed August 29, 1921. Serial No. 496,716. Term of patent 14 years.

To all whom it may concern:

Be it known that I, OSCAR BROCKMAN, a citizen of the United States, residing at Louisville, in the county of Jefferson and State of Kentucky, have invented a new, original, and ornamental Design for a Vending Vehicle, as shown in the accompanying drawing and described in the following specification.

The drawing shows a vehicle embodying my design in perspective.

I claim:

An ornamental design for vending vehicles as shown.

OSCAR BROCKMAN.
